UNITED STATES PATENT OFFICE.

RAY P. JACKSON, OF SWISSVALE, PENNSYLVANIA, ASSIGNOR TO WESTINGHOUSE ELECTRIC AND MANUFACTURING COMPANY, A CORPORATION OF PENNSYLVANIA.

LIGHTNING-ARRESTER.

1,031,795.

Specification of Letters Patent.

Patented July 9, 1912.

Application filed October 8, 1910. Serial No. 586,078.

To all whom it may concern:

Be it known that I, RAY P. JACKSON, a citizen of the United States, and a resident of Swissvale, in the county of Allegheny 5 and State of Pennsylvania, have invented a new and useful Improvement in Lightning Arresters, of which the following is a specification.

My invention relates to lightning arresters and it has special reference to such devices of this character as are adapted for relatively low-voltage service.

The object of my invention is to provide a simple and durable device of the character above indicated that shall embody specially constructed arcing members and a magnetic blow-out for extinguishing the electric arcs which may be formed between the arcing members upon the occurrence of 20 a static discharge.

For relatively low-voltage service, it is desirable, in order to secure adequate protection by means of a lightning arrester, to set the opposed arcing members very closely 25 together, but, if the members are rigidly fixed at a slight distance apart, a magnetic blow-out does not operate readily in disrupting the arc. It has, accordingly, been my aim to provide opposed arcing members 30 which will be automatically separated when an electric arc is formed between them.

According to my present invention, I provide a lightning arrester having opposed arcing members, each of which consists of 35 a horn-shaped end member and a yielding shank, to which the end member is secured, the two shanks being connected electrically to terminal members to which they are riveted, or otherwise secured, and the 40 two horns being adjacent to each other and diverging outwardly. The two horns are constructed of copper, or other conducting material, and are located in a magnetic field produced by a suitable blow-out coil.

Figure 1 of the accompanying drawings is a diagrammatic view of a lightning arrester embodying my invention; Fig. 2 is a 45 sectional elevation, and Fig. 3 is a front view of a preferred embodiment of my invention, with the frame open.

Referring to the drawings, the structure here shown comprises a frame or box composed of two hinge-connected parts 1 and 2, a pair of terminal members 3 and 4 secured 50 to an insulating plate or base 5 of the part

1, opposed arcing members 6 and 7 yieldingly connected to the terminal members 3 and 4 by means of spring shanks 8 and 9, a blow-out magnet coil 10 and a resistor 11. The blow-out magnet coil 10 and the 60 resistor 11 are both secured to the part 2, the coil 10 being so located, with reference to the members 6 and 7, that a magnetic field is produced at the point of minimum air gap between the members when electric current traverses the said coil. The part 1 of the box is provided with an arc chute 12 which is similar in construction to the arc chutes ordinarily found in magnetic blow-out switches, car circuit breakers and the 70 like. The members 6 and 7 are separated by a rib or projection 13 on the base 5 having an enlargement 14 at its free end. The arcing member 7 is provided with a set screw 15 which projects through the member and 75 engages the enlargement 14 of the projection 13 to prevent the arcing members from vibrating into engagement with each other, the member 6 being limited, either in the same manner or directly by the enlargement 80 14.

The circuit connections for the device are shown in Fig. 1 of the drawings, to which special reference may now be had. One terminal 16 of the resistor 11 and one terminal 85 of the blow-out coil 10 are connected together and to a circuit conductor 17, the opposite terminals of the resistor and the coil being joined to the arcing member 6, and the other arcing member 7 being connected to 90 circuit conductor 18. The arrangement of parts is such that, under normal conditions, no current traverses the blow-out coil or any part of the arrester, but, when a discharge takes place between the members 6 and 7, 95 a circuit is completed through the blow-out coil and the resistor, in multiple, and across the air gap between the members 6 and 7. The arc which is produced between the members is choked by the magnetic field 100 produced by the coil 10, and the torque exerted by the magnetic flux upon the members 6 and 7, by reason of the current flowing through them, forces the arcing members slightly apart and assists in disrupting 105 the arc. By dividing the box into two hinge-connected parts and mounting certain members on each part, they are all readily accessible for inspection and repairs.

Structural modifications may be effected 110

within the spirit and scope of my invention, and I desire that only such limitations shall be imposed as are indicated in the appended claims.

5 I claim as my invention:

1. A lightning arrester comprising a pair of opposed yielding discharge members and means for producing a magnetic field between said members to force them apart and 10 extinguish such arcs as may be formed between them.

2. A lightning arrester comprising a pair of opposed horn-shaped arcing members, yielding shanks therefor, means for producing a magnetic field in the vicinity of 15 the members and adjustable means for de-

termining the minimum air gap between them.

3. A lightning arrester comprising a pair of yielding arcing members, means for determining the minimum air gap between them, and a magnetic blow-out coil, energized when a discharge takes place across the gap, for influencing the yielding members and extinguishing the arc. 20

In testimony whereof, I have hereunto subscribed my name this 24th day of Sept., 1910.

RAY P. JACKSON.
